UNITED STATES PATENT OFFICE.

GODFREY FUGMAN, OF CLEVELAND, OHIO.

METALLIC SHEET FOR USE IN CONSTRUCTING BUILDINGS.

SPECIFICATION forming part of Letters Patent No. 634,237, dated October 3, 1899.

Application filed February 18, 1899. Serial No. 705,997. (No model.)

To all whom it may concern:

Be it known that I, GODFREY FUGMAN, a resident of Cleveland, county of Cuyahoga, and State of Ohio, have invented certain new and useful Improvements in Metallic Sheets or Bodies for Use in the Construction of Buildings, &c.; and I do hereby declare the following to be a full, clear, and exact description of the invention, such as will enable others skilled in the art to which it pertains to make and use the same.

My invention relates to improvements in a metallic body for floors and walls of buildings.

15 The primary object of the invention is to provide a metallic sheet or body that is more especially designed for fireproof construction and for the formation of the body portion of cement or plaster for walls or floors of buildings and that comprises a construction that is simple and durable and is not shrunk or shortened, expanded or enlarged, or weakened during the process of manufacture and is capable of adding materially to the strength of 20 the walls or floors.

With this object in view and to the end of realizing other advantages hereinafter appearing the invention consists in features of construction hereinafter described, and pointed 25 out in the claims.

In the accompanying drawings, Figure I is a plan of a slotted metallic sheet employed in forming my improved metallic body. Fig. II is a plan showing the metallic body that is 30 formed from the sheet illustrated in Fig. I. Fig. III is an end elevation of the body. Fig. IV is a section on any one of lines IV IV, Fig. II, looking in the direction of the arrow, and shows only the portion of the body through 35 which the section is taken. Fig. V is a section on line V V, Fig. II, looking in the direction of the arrow, and shows only the portion of the body through which the said section is taken.

40 My improved metallic body, that, as already indicated, is more especially designed for use in plaster-work or cement-work, is made from a metallic sheet (shown in Fig. I) and provided with any suitable number of 45 rows of preferably parallel slits *a*, extending transversely of the respective row and having opposite end portions of the slits conver-

ging toward the central portion of the slit—that is, each slit has diverging portions between its central portion and end extremities. 55 In the case illustrated the sheet is provided with three parallel rows of slits, and the slits of each row of slits are parallel. The rows of slits are arranged a short distance apart, so as to leave a plain and unslotted portion 60 between adjacent rows of slits, and the outer rows of slits are separated a suitable distance from the adjacent side edge of the sheet, so as to leave the sheet plain and unslotted next to the said edge. The portions of the sheet 65 between adjacent slits of each row of slits is bent laterally in any approved manner, so as to form a wing *b*, projecting laterally from the sheet, and the portions between the slits of each row of slits are bent, preferably, alternately in opposite directions, so as to form two rows of wings upon opposite sides, respectively, of the sheet and so that the wings of each of the said rows shall alternate with the wings of the other row. It will be observed, therefore, that by slitting the sheet 70 as aforesaid and then laterally bending the sheet's portions between the slits in the manner hereinbefore indicated rows of wings are formed upon each side of the sheet, that the 75 wings of each row of wings are parallel and arranged a suitable distance apart, and that the wings of each row of wings upon one side of the sheet alternate with the wings of the opposite row of wings upon the other side of 80 the sheet. I would remark also that the wings of each row of wings upon each side of the sheet are arranged, preferably, so as to alternate with the wings of the adjacent row or rows of wings upon the same side of the 85 sheet, and in the case illustrated, therefore, the wings of the central row of wings (shown very clearly in Fig. V) at each side of the sheet alternate with the wings of the outer rows (shown very clearly in Fig. IV) upon 90 the said side of the sheet.

The slitting and bending of the sheet's portions between the slits in the manner hereinbefore described form, of course, apertures *c* in the sheet between the wings *b*, and the said 95 apertures accommodate the reception and passage of plaster or cement in the construction of floors, walls, &c., involving the use of my improved metallic body.

In using my improved metallic sheet or body in wall construction I would remark that the sheet or body would be run from floor to floor and attached to the floor-supports in any approved manner and supported, furthermore, by metallic posts or studding made of angle-iron or other metallic forms.

What I claim is—

1. As an article of manufacture, a metallic sheet provided with rows of slits, and having the portions of the slits between the latter's ends and central portion diverging from the central portion so that the portions of the sheet between two adjacent slits of a row of slits can be bent laterally to form a laterally-projecting wing.

2. A metallic sheet provided with parallel rows of slits and having the slits of each row

of slits parallel and diverging between their central portion and their ends.

3. A metallic body of the character indicated, consisting of a metallic sheet provided with suitably - arranged lateral projecting members formed, respectively, by providing the sheet with two slits arranged a suitable distance apart and diverging from their central portion toward their ends, and then bending the sheet's portion between the slits laterally.

Signed by me, at Cleveland, Ohio, this 16th day of February, 1899.

GODFREY FUGMAN.
